UNITED STATES PATENT OFFICE.

ROBERT PENNEL WALKER, OF ASHEVILLE, NORTH CAROLINA, ASSIGNOR TO THE
NEUFFED COMPANY, OF ASHEVILLE, NORTH CAROLINA, A CORPORATION OF
NORTH CAROLINA.

COMPOSITION FOR AND PROCESS OF TREATING TYPE-WRITER PLATENS.

1,264,721.

Specification of Letters Patent. Patented Apr. 30, 1918.

No Drawing.

Application filed February 21, 1917. Serial No. 150,211.

To all whom it may concern:

Be it known that I, ROBERT PENNEL WALKER, a citizen of the United States, residing at Asheville, in the county of Buncombe and State of North Carolina, have invented a certain new and useful Composition for and Process of Treating Type-Writer Platens, of which the following is a specification.

10 The present invention relates to a composition of matter which is primarily adapted for use in connection with the rubber rolls of typewriter platens or the like.

One object of the invention is to overcome 15 the disadvantage of a slippery surface on typewriter platen rolls, to which end, one feature of the invention consists in providing a composition of matter that, when applied, will form a coating over the surface 20 of the platen and prevent undue slipping of the paper when used in the machine.

Another object of the invention is to provide a composition of matter which will improve the condition of the platen, to which 25 end, another feature of the invention consists in providing a composition of matter which will prevent the platen from being exposed to atmospheric conditions, and in this manner preserve the life of the rubber, the 30 composition having also a tendency to fill up the pores as well as the indentations in the platen caused by the contact of the type.

Heretofore, considerable difficulty has been 35 experienced in overcoming the bad effects of a slippery typewriter platen. Certain solutions have been employed with these ends in view, but these solutions have generally proven of merit only temporarily.

40 In carrying out the invention and to obtain the best results, it is preferred to use the following ingredients in about the proportions named. Two pounds of thoroughly crushed lump rosin, one ounce shellac and 45 one gallon denatured alcohol placed in an air-tight vessel, and allowed to stand until completely dissolved, which requires about 12 to 15 hours. This mixture is then strained or filtered into a glass receptacle 50 and then is added one ounce of oil of sassafras. To this is added one-half ounce of coloring composed of one gallon alcohol and eight grains of fuchsin. When thoroughly

mixed, the composition is exposed to the sunlight for two days when it may be bottled 55 ready for use.

The alcohol employed in the solution in addition to dissolving certain ingredients in the formula is also of value when the composition is used to clean carbon off the rubber 60 platen roll of the typewriter and as it evaporates very quickly, it leaves the other ingredients evenly and sparingly distributed over the surface of the rubber producing the desired results. The composition may be 65 applied to the platen of the typewriter in any effective manner, preferably by a clean cloth. While the composition quickly dries, better results may be obtained by rubbing the solution onto the platen. The applications 70 may be repeated as often as is necessary to obtain the desired results.

While it is preferred to use the above ingredients and the particular manner of mixing the same, it is to be understood that 75 other ingredients having the same descriptive properties may be employed without departing from the spirit of the present invention. Furthermore, it should be understood that while the invention is described 80 as being especially adapted for use in connection with rubber rolls of typewriter platens, the same could be also used to advantage on other friction surfaces in like devices where it is desirable to overcome 85 undue slipping of the friction surface and the device contacting therewith.

I claim:—

1. The process of treating friction surfaces to induce adhesion with objects contacting therewith, which consists in coating the same with a tacky substance containing a non-oily evaporating medium.

2. The herein described composition of matter for treating the rubber rolls of typewriter platens consisting of two pounds of lump rosin, one ounce of shellac, one gallon denatured alcohol, one ounce of oil of sassafras and a one-half ounce solution of coloring matter composed of one gallon of 100 alcohol and eight grains of fuchsin.

The foregoing specification signed at Asheville, N. C., this 19th day of February, 1917.

ROBERT PENNEL WALKER.
